Adam Hampton, New York, New York.
Letters Patent No. 21, dated May 17th 1844.

The Schedule referred to in these Letters Patent and making part of the same. —

To all whom it may concern. —

Be it known that I, Adam Hampton of 87, Fulton Street of the City of New York in the State of New York have invented or produced a new design for a Mantel Grate and I do hereby declare that the following is a full and exact description of the same referred to the annexed drawing.

The Mantel Grate is made of cast iron and it has its frame A A A shown upon the elevation projecting in the manner shown upon the Plan by the letters A A. The bottom part of the frame has openings B B and the top part of it from C to C is perforated. The mouldings of the frame are shown upon the Plan, section and the embellishments which are of the Greek style of art are fully exhibited upon the elevation and upon the drawings which has been deposited by me in the Patent office.

What I claim and wish to secure by Letters Patent is the Design for a New Mantel Grate having its frame projecting as above described and its embellishments as shown upon the drawings.
